CLAIM

The ornamental design for a display screen with an animated graphical user interface, as shown and described.

DESCRIPTION

FIG. 1 is a first image for a display screen with an animated graphical user interface;

FIG. 2 is a second image thereof;

FIG. 3 is a third image thereof;

FIG. 4 is a first image of a second embodiment thereof;

FIG. 5 is a second image thereof; and,

FIG. 6 is a third image thereof.

The appearance of the animated graphical user interface sequentially transitions between FIGS. 1 to 3 and FIGS. 4 to 6. The process or period in which one image transitions to another image forms no part of the claimed design. The broken lines showing of the display screen and the graphical elements in all views form no part of the claimed design.
